UNITED STATES PATENT OFFICE

149,705

DESIGN FOR A TOY AIRCRAFT OR THE LIKE

Henry Struck, Old Lyme, Conn.

Application July 31, 1946, Serial No. 132,151

Term of patent 3½ years

(Cl. D34—15)

To all whom it may concern:

Be it known that I, Henry Struck, a citizen of the United States, residing at Old Lyme, county of New London, State of Connecticut, have invented a new, original, and ornamental Design for a Toy Aircraft or the Like, of which the following is a specification, reference being had to the accompanying drawings, forming part thereof.

Fig. 1 is a perspective view of a toy aircraft, showing my new design.

Fig. 2 represents a side elevation thereof.

Fig. 3 represents a front elevation thereof.

Fig. 4 represents a rear elevation thereof.

I claim:

The ornamental design for a toy aircraft or the like, as shown.

HENRY STRUCK.
